UNITED STATES PATENT OFFICE.

GEORGE S. STRONG, OF NEW YORK, N. Y., ASSIGNOR TO JOHN P. MURPHY,
OF PHILADELPHIA, PENNSYLVANIA.

CRANK-SHAFT.

SPECIFICATION forming part of Letters Patent No. 637,300, dated November 21, 1899.

Original application filed December 15, 1898, Serial No. 699,312. Divided and this application filed May 5, 1899. Serial No. 715,695. (No model.)

To all whom it may concern:

Be it known that I, GEORGE S. STRONG, a citizen of the United States of America, residing in the city, county, and State of New York, have invented a certain new and useful Improvement in Crank-Shafts and Fly-Wheels, of which the following is a true and exact description, reference being had to the accompanying drawings, which form a part thereof.

My invention relates to the construction of fly-wheels and the method of securing them to crank-shafts, and is especially designed for use in connection with gas-engines and for the purpose of relieving the crank-shaft from the weight of the fly-wheel and carrying it directly on a bearing in the frame of the machine.

The nature of my improvements will be best understood as described in connection with the drawings, in which they are illustrated in connection with a gas-engine, which, as shown, is one forming the subject-matter of my application for Letters Patent filed December 15, 1898; Serial No. 699,312, of which application the present one is a division.

My invention is also shown in connection with a fly-wheel and adjustable crank-pin moving therein, which forms the subject-matter of another pending application—to wit, that filed by me December 8, 1898, Serial No. 698,623.

Referring now to the drawings, in which my invention is illustrated, Figure 1 is a plan view of the engine provided with my improvements, shown partly in section; and Fig. 2 is a cross-section on the line 2 of Fig. 1.

A and A' indicate cylinders of the gas-engine, in which move pistons B and B', coupled through connecting-rods D and D' with cranks C' and C² of the crank-shaft C.

F indicates a casing thrown around the cranks of the engine, and F' an extension from the casing, forming a bearing for the stud-shaft of the fly-wheel, as will hereinafter be described. Another somewhat similar extension F² forms a bearing at the other side of the engine for the crank-shaft.

F² is an annular chamber formed in the extension F' for a worm-wheel, (indicated at K.)

F³ and F¹⁵ are bearings for the shaft K², and F¹³ and F¹⁴ bearings for the shaft I⁴. The shaft K² is actuated through gearing (not shown) by the worm-wheel K and working through a universal joint (indicated at K³) 55 actuates a shaft, the end of which is indicated at K⁴ and to which are attached cams arranged to actuate the valves of the engine. The shaft I⁴ has attached to it a hub, (indicated at I³), from which extend arms I² I², 60 engaged with a ring I, which in turn is actuated by a governor H, secured on and operated by the shaft C of the engine. The motion thus imparted to the shaft I⁴ is communicated by a lever (indicated at I⁵) to a rod 65 I⁶, which enters the valve-box N and regulates the adjustment of certain cams, (not shown,) which are actuated by the shaft K⁴.

P indicates the head proper of the gas-engine cylinders. 70

E is the fly-wheel of the engine, which is formed with a transverse cylindrical channel, in which moves the piston, (indicated at E²,) to which in turn is secured the crank-pin E', which pin is adjusted to and from the center 75 of the fly-wheel by the movement of the piston, while the movement of the piston is effected by fluid under pressure introduced to its end through a channel e, which communicates, as shown, with a channel c in the crank-shaft and through said channel in the crank-shaft with a pump or other device, by which the fluid is introduced or withdrawn in order to shift the crank-pin.

Referring now to the features which constitute the subject-matter of my present invention, the fly-wheel E is formed with a centrally-projecting stud-shaft E³, having near the wheel a threaded perforation E⁴, which near the outer side of the stud-shaft opens into an 80 enlarged unthreaded perforation E⁵. The end of the shaft C enters and fits in the unthreaded perforation E⁵ and is provided, as shown, with a threaded extension C' of smaller diameter, which screws into the threaded perforation E⁴, thus securing the shaft and the stud-shaft of the fly-wheel together. The bearing F' surrounds the stud-shaft E³ and forms directly a bearing for this stud-shaft 85 and only indirectly a bearing for the shaft 90 95 100

C, and in this way I carry the weight of the fly-wheel directly on the bearing instead of making the bearing act directly on the shaft and carrying the weight of the fly-wheel on the shaft.

Preferably I construct the bearing, as shown, with a hardened-steel liner (indicated at F⁷) and provide a similar hardened-steel liner f⁷ for the stud-shaft E³, placing between these liners a series of rollers F⁸, so as to provide a roller-bearing to diminish friction.

Having now described my invention, what I claim as new, and desire to secure by Letters Patent, is—

15 1. In a gas-engine, a crank-shaft in combination with a fly-wheel, as E, a hollow stud-

shaft E³ extending from the center of said fly-wheel, said shaft extending over and being secured to the end of the crank-shaft, and a shaft-bearing for said stud-shaft in the framing of the engine.

2. In a gas-engine, a crank-shaft in combination with a fly-wheel, as E, a hollow stud-shaft E³ extending from the center of said fly-wheel, said stud-shaft extending over and being secured to the end of the crank-shaft, and a roller-shaft bearing for said stud-shaft in the framing of the engine.

GEORGE S. STRONG.
